UNITED STATES PATENT OFFICE.

ALVIN O. CARMAN, OF POTTERVILLE, MICHIGAN.

SHOE-FASTENING.

SPECIFICATION forming part of Letters Patent No. 339,146, dated April 6, 1886.

Application filed January 22, 1886. Serial No. 189,384. (No model.)

To all whom it may concern:

Be it known that I, ALVIN O. CARMAN, of 5
Potterville, in the county of Eaton and State
of Michigan, have invented certain new and
useful Improvements in Shoe-Fastenings; and
I do hereby declare the following to be a full,
clear, and exact description of the invention,
such as will enable others skilled in the art
to which it appertains to make and use the
same.

My invention relates to fastenings for over-
shoes, and is also applicable to other kinds
of shoes; and the object of my invention is
to produce a simple and inexpensive fasten-
ing which will securely connect the flaps of
the shoe, and which may be easily manipu-
lated.

To the above purposes my invention con-
sists in an eccentrically-pivoted lever de-
signed to be attached to one flap of the shoe,
and provided with a stud for engaging the
slots of a catch-plate secured to the opposite
flap of the shoe.

My invention also consists in certain pec-
uliar and novel features of construction and
arrangement, as hereinafter described and
claimed.

In order that my invention may be fully
understood, I will proceed to describe it with
reference to the accompanying drawings, in
which—

Figure 1 is a perspective view of an over-
shoe with my improved fastening applied
thereto. Fig. 2 is a detached view showing
two forms of construction of the fastening-
lever and the rivet for securing the fastening-
lever to the shoe-flap.

In the said drawings, A designates an over-
shoe, and a a' its flaps. To the flap a' is at-
tached, in any suitable manner, the catch-
plate b, having one or more slots, b', extending
transversely to the length of said plate.

c designates my improved fastening-lever,
which is of approximate L shape, the two
arms of the lever meeting at a somewhat acute
angle. The arm c' of said lever is enlarged,
so as to properly receive the rivet d, by which
the lever is pivoted to the flap a'. This rivet
has two flanges, d' and d'', between which the
body of the flap is confined, and a head, d',
between which and the flange d'' the lever is
freely confined. The outer end of the arm c'
of the lever should be turned somewhat up-

ward, to afford an easy hold upon the lever.
Upon the portion c of this lever is formed a 55
T-shaped stud, c'', which stands erect from
the portion c, and which may be either formed
separately and attached to the lever or
punched out therefrom and properly bent up.
It will thus be seen that by inserting the stud
c'' into one of the slots b' and then turning
the lever so that its arm shall rest against the
outer edge of the plate b, the flaps of the shoe
will be securely connected, and no pulling
strains can separate the parts of the fasten- 65
ing. By simply throwing the lever in the
opposite direction till the arm c' lies parallel
with the outer end of the plate and the head
of the stud c'' lies parallel with the slots b'
the parts of the fastening may be readily sepa- 70
rated.

This device may be quickly and readily ma-
nipulated even with the hands gloved. The
parts of the device may also all be made
cheaply of sheet metal.

Having thus described my invention, what I
claim as new, and desire to secure by Letters
Patent, is—

1. In a fastener for shoes, the combination,
with a catch-plate secured to one flap of the 80
shoe and having an opening or slot therein,
of a lever loosely secured to the other flap of
the shoe and provided with a stud adapted
to engage the slot or opening in the catch-
plate, all arranged to operate substantially as 85
set forth.

2. The lever having arms c c', arranged as
described, and provided with the stud c'' upon
its arm c, substantially as and for the purpose
set forth.

3. The combination, with the transversely-
slotted plate b, of the lever having arms c c'
and stud c'', substantially as and for the pur-
pose specified.

4. A shoe having a flap carrying the slot-
ted plate b, and an opposite flap carrying the
eccentrically-pivoted lever having the arms
c c' and T-shaped stud c'', as described.

In testimony whereof I have signed this
specification in the presence of two subscrib- 100
ing witnesses.

ALVIN O. CARMAN.
